JAR SEALER

James Eugene Polisso, Rochester, Pa., assignor of
one-third to Thomas D. Stablow, Rochester, Pa.

Application May 22, 1935, Serial No. 22,848

1 Claim. (Cl. 81—15.1)

This invention relates to jar sealers, and its general object is to provide a sealing device that is primarily designed for use on caps of Mason jars and the like for removing kinks, raised places 5 and the like from the flanged lower edge of the skirt thereof, with the result the edge will be straightened and made uniform throughout its circumference so as to cooperate with the rubber sealing element or gasket to provide a perfect 10 and air-tight joint between the jar and its cap.

Another object of the invention is to provide a jar sealing device for the purpose of reshaping jar caps so that they can be used from time to time, and the device accomplishes its function in 15 an easy and expeditious manner, with very little effort on the part of the operator.

A further object of the invention is to provide a jar sealing device that includes a body formed from a single piece of sheet metal, in a manner 20 to provide opposite walls that have journaled thereto, cap flange engaging rollers to straighten the flange for the purpose previously set forth.

A still further object of the invention is to provide a jar sealing device, that is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein 35 like characters denote like or corresponding parts throughout the several views, and in which:

Figure 1 is a top plan view of the sealing device which forms the subject matter of the present invention.

40 Figure 2 is a side view thereof.

Figure 3 is a vertical sectional view taken through the device and illustrates the same in applied position.

Referring to the drawing in detail, it will be 45 noted from Figure 3 that I have illustrated my device as being applied to the cap of the usual Mason jar, and for distinction, the cap is indicated by the letter A and the jar by the letter B.

The body of my device is hollow and preferably 50 formed from a single piece of sheet metal into octagon shape, and includes a top 1 having depending from each of the straight edges thereof a wall 2. The walls of course have their side edges integral. Due to the octagon shape of the 55 body, it will be obvious that eight depending walls

or portions are provided that are disposed at an angle with respect to each other, consequently the body can be gripped at any place desired, as the walls provide a convenient gripping surface, during the use of the device, as will be apparent. The top 1 may be flat but I have shown a plurality of concentrically arranged annular ribs 3 formed therein and rising therefrom, as best shown in Figure 3.

While I preferably provide four cap flange engaging rollers, any number may be employed, providing they are arranged to balance each other. These rollers are indicated by the reference numeral 4 and are in the form of disks shaped to provide annular beads 5, the outer walls of which 10 are inclined outwardly to form flange engaging 15 faces 6.

In the form as shown, the rollers 4 are journaled to certain of the walls 2 which are disposed opposite each other as best shown in Figure 1, and the journals are in the form of headed pins 7 having bearings 8 to receive the rollers and for disposing them inwardly of the walls, as best shown in Figure 3. The pins may be riveted or otherwise secured to the walls, as will be apparent, but in 20 any event, the flange engaging faces extend below 25 the lower edge of the walls, to allow ample space between the lower edge and the top of the body of the jar B.

From the above description and disclosure of 30 the drawing, it will be obvious that I have provided a jar sealing device that is primarily designed for reshaping the flanged lower edges of 35 jar caps, and in the use of my device, the cap A is applied to the jar B in the usual manner, and of course with the gasket between the flange of the cap and the gasket receiving seat. The device is then arranged, with the body enclosing the cap so that the rollers engage the lower edge thereof, as shown in Figure 3. The device is rotated 40 while applying slight pressure thereto, with the result kinks, raised places and the like are removed from the lower edge, therefore the latter will cooperate with the sealing element or gasket to provide a leak proof and air-tight connection 45 between the cap and jar.

It is thought from the foregoing description that the advantages and novel features of my invention will be readily apparent.

I desire it to be understood that I may make 50 changes in the construction and in the combination and arrangement of the several parts, provided that such changes fall within the scope of the appended claim.

What I claim is:

A jar cap sealing device comprising a hollow sheet metal body including a closed flat top, concentrically disposed annular ribs formed on and rising from the top to reinforce the same, walls 5 formed on and depending from the top to provide a jar cap receiving chamber, said walls being integral and disposed at an angle with respect to each other to provide flat hand gripping surfaces,

disk rollers journaled to certain opposed walls and arranged within the chamber, and said rollers shaped to provide hollow annular beads at the peripheries thereof, with the outer walls of the beads outwardly flared in rounded formation to provide cap flange engaging surfaces. 5

JAMES EUGENE POLISSO.
